UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

IMPLEMENT FOR APPLYING AND FASTENING PACKAGE BINDERS.

Application filed December 9, 1919. Serial No. 343,555.

To all whom it may concern:

Be it known that I, SPENCER C. CARY, a citizen of the United States, residing at the city of New York, borough of Brooklyn, county of Kings, and State of New York, have invented a certain new and useful Implement for Applying and Fastening Package Binders, of which the following is a specification.

10 This invention is an implement for applying and fastening the binders, composed either of wire or flat metal strapping, to various kinds of shipping packages, such as boxes, crates, shooks, etc.

15 In this art, it is desirable that a binder be applied under tension to a shipping package, in order that the components of such package may be bound firmly to resist rough usage or handling in transportation; but it 20 has heretofore with implements for the application of such binders been a difficult operation to fasten, lock or seal the end portions of the binder, more especially after stretching the same tightly around the package.

25 According to this invention, the implement embodies in one instrumentality means for placing tension upon the binder, and means for fastening the end portions of said binder subsequent to the operation of stretching the latter.

30 The binder-stretching means includes a plurality of movable heads retained in operative relation by a guide rod and, each head being provided with a binder-gripping device. In a preferred form, the implement as an entirety is mounted for service over a suitable bench or table by attaching the before mentioned guide rod to a carrying member in the form of a crosshead, the latter being mounted upon a post attached for vertical adjustment in a suitable clamp provided on the bench or table, whereby the entire implement may be raised or lowered 45 as required to adapt it for use in connection with boxes etc. of different sizes.

35 The binder-fastening means is mounted in an operative position with respect to said heads of the binder-stretching means, where- 50 by said binder-fastening means is adapted for operation upon the slack or free end portions of a binder the major portion of which is under tension by the action of said binder-

stretching means.

The binder fastening means is thus directly associated with or related to the stretching means for the performance of its function of locking or sealing the binder prior to releasing said binder from the action of said stretching means. In the several operations, it is desirable that the binder-fastening means be so positioned that in the work of placing tension upon the binder said fastening means shall be out of the way of the operator, and to these ends it is preferred to support or mount said binder-fastening means by devices which enable the latter to be shifted at will into an out-of-service relation to the binder-stretching means.

70 The binder fastening means are embodied in different constructional forms, the form being dependent upon the character of the binder used in connection with the package. In the case of a wire binder, the fastening means embodies a seal retaining member and a plurality of other members mounted for rotative movement with respect to said retaining member and operable at will for bending or twisting the slack or free end 75 portions of said wire binder into locking or interlocking relation to a seal member under the restraint of the first named or retaining member.

80 For fastening and sealing the end portions of a flat metal band, commonly known as box strapping, the fastening mechanism embodies a plurality of cooperating members and means such as a cam lever or a screw for applying pressure thereto so as to upset 85 the metal of said band end portions and interlock the same with a seal member.

85 In either form of said binder locking means the operative parts or elements thereof are supported by suitable means, such as a 90 swinging arm, connected loosely to the guide rod in such manner that said binder locking means may be moved into operative position relatively to the end portions of a binder, and then operated to perform the function 95 of fastening or locking the slack end portions of the binder while the remainder of said binder is under tension.

100 Furthermore, in either of the preferred forms of the binder fastening means the 105 parts thereof are adapted for use in conjunc-

tion with the binder and with a seal member, the latter being readily positioned in contact with the free or slack end portions of the binder, and the several parts being 5 locked or fastened so as to perform the function of a seal, the latter adding materially to the security of the shipping package.

Other functions and advantages of the invention will be set forth in the following 10 description taken in connection with the annexed drawings, wherein—

Fig. 1 is a side elevation of an implement for stretching a binder around a packing case, and for sealing the end portions of 15 said binder in accordance with this invention, said implement being shown in an operative position with respect to the shipping package resting upon a bench or table.

Fig. 2 is a plan view of the implement 20 shown in Fig. 1.

Fig. 3 is a vertical sectional elevation taken in the plane of the dotted line 3—3 of Fig. 2, illustrating a part of the binder stretching means, and showing more particularly certain elements of the binder fastening or sealing means.

Fig. 4 is an elevation, partly in section, of the binder sealing means looking toward the left of Fig. 3.

Fig. 5 is an inverted or bottom plan view 30 of the binder sealing means illustrated in Figs. 3 and 4.

Fig. 6 is a vertical cross section taken in the plane of the dotted line 6—6 of Fig. 2, 35 looking in the direction of the arrow.

Fig. 7 is a detached perspective view of the bending jaws and the rotatable head therefor forming certain elements of the binder sealing means.

Fig. 8 is a horizontal section through a binder seal with the end portions of a binder 40 locked to said seal.

Fig. 9 is a detail perspective view of the binder seal shown in Fig. 8, and detached 45 from the end portions of the binder.

Fig. 10 is a plan view of the implement including the binder stretching means and another form of the binder locking means, the latter being adapted more particularly 50 for operation upon the end portions of a flat metal strap.

Fig. 11 is a vertical cross section taken in the plane of the dotted line 11—11 of Fig. 10 looking in the direction of the arrow and 55 illustrating more particularly the operation of the binder sealing means upon a seal and the end portions of a flat metal strap constituting the binder.

Fig. 12 is a vertical cross section on the 60 line 12—12 of Fig. 11.

Figs. 13 and 14 are fragmentary detail 65 perspective views of the complementary jaws of the binder strap upsetting mechanism adapted for use in conjunction with a seal.

Fig. 15 is a perspective view of the seal

adapted to be used in connection with the flat strap which is placed under tension by the operation of the stretching means illustrated in Fig. 10.

Fig. 16 is a detail plan view of the flat 70 metal strap and the seal therefor.

The implement is supported in an operative position by a supporting member A shown in Figs. 1, 2 and 6 as a horizontal crosshead. Said crosshead is supported by 75

suitable means on a work bench or table indicated at B in Figs. 1 and 2, said supporting means being shown as a post a attached rigidly to the crosshead and fitting in a sleeve b secured in a desirable way to one 80 side of the bench or table. The post a passes loosely through sleeve b so that it may be raised or lowered as desired, and the post is held fixedly in position by binding screw b' supported in sleeve b and adapted for frictional contact with the post whereby provision is made for raising and lowering the supporting head A in order that the binder stretching means and the binder locking means may be used in connection with pack- 85

ing cases or other shipping packages of different sizes. One of said packing cases is indicated at X in Fig. 1, and it is adapted to receive a binder x which is stretched around the packing case so that the end portions of the binder may be locked, the binder x of Figs. 1, 2, 3 and 8 being shown as a wire, the ends of which are locked to a seal x', shown in Figs. 1, 3, 8 and 9.

The binder-stretching means illustrated in 90 Figs. 1, 2, 6 and 10 includes a guide rod C, a plurality of gripper heads D, E, and an operating screw F. The guide rod C is rigidly attached to the supporting head A, one

end portion of said rod being received in an 105 aperture provided in said head, and the rod being locked in position by a transverse pin c. The gripper heads D, E are fitted loosely on rod C so as to have sliding and rotative movement thereon. Each head D or E is 110

provided intermediate its ends with an opening d which is internally threaded, and at one end said gripper head is provided with a fixed jaw d', see Fig. 6. Said jaw-formed end of the gripper head is provided, also, 115

with a recess d'', and within this recess is positioned a movable jaw d³ and the head of a cam lever d⁴. The movable jaw d³ is in op- 120

posing relation to the fixed jaw d', said jaws being relatively positioned to leave an intervening space which opens downwardly, whereby the jaws d' d³ cooperate so as to have engagement with a binder wire x while 125

the latter is in close relation to or actual contact with the shipping package X, as a result of which the binder can be placed under tension for the major part of its length without lifting said binder for an appreciable distance away from the shipping package. The jaw d³ is under the action of a 130

spring d^s , shown in dotted lines in Fig. 6, and with this jaw contacts the cam head d^s of lever d^t , said cam head being pivoted to the forked end of the gripper head by a transverse pin d^7 , see Fig. 6. It will be understood that each head D and E is provided with the fixed jaw and the movable jaw, and, further, that each head is provided with the cam lever d^t , as clearly shown in Figs. 1, 2 and 10.

The operating screw F is provided with a right-hand thread for a part of its length and with a left-hand thread for another part of its length, said threaded parts of the screw having engagement with the threaded aperture d of heads D, E, respectively, whereby the rotation of the screw imparts relative movement simultaneously to the heads D, E so as to move them toward or from each other, whereby the stretching device is adapted to pull in two directions upon the end portions of the binder. The screw is rotated by any preferred means, a crank f being shown. In this invention the binder stretching mechanism is shiftable at will into an out-of-service position with respect to the packing case for the purpose of permitting said packing case to be placed upon table or bench B and the binder x to be readily passed around the packing case before bringing the stretcher mechanism into position for service. To this end, the supporting head A is provided with a slot or recess e , see Fig. 6, the same being of arcuate form and having as its axis the centre of the guide rod C. Furthermore, the screw F is provided with a smooth portion f' and with a collar f^2 whereby said smooth portion f' of the screw is adapted to occupy recess or slot e when the binder stretching means is in an operative position. The collar f^2 and an end portion of the crank f engage with the respective sides of the supporting head A when the binder stretcher is in position for service so that the collar and the crank cooperate with the head in precluding endwise movement of the screw in the operation of imparting movement to the heads D E. In order to shift the binder stretching means into the out-of-service position the operator lifts the screw F upwardly and during this lifting movement the gripper heads D E turn freely on the guide rod C, the screw F being lifted out of the recess e of the supporting head A and the entire device turning on the rod C so as to shift the binder-stretching means away from the packing case and thereby expose that part of the packing case around which it is desired to place the binder x preliminarily to the operation of stretching it.

In the construction shown, the operating screw is adapted for supporting a carrying member of the binder-locking or sealing means, and to this end the middle portion of said screw is plain or unthreaded for a

part of its length, as at g , said plain part of the screw being provided with an annular groove, indicated at g' in Fig. 3. On said plain part of the screw is loosely fitted a collar g^2 of a carrying member G, shown in Figs. 1, 2, 3 as an arm extending radially from the screw F. This collar of the arm G is free to turn on the plain part of the screw, but said arm is held from sliding movement in a direction lengthwise of the screw F by a retaining screw g^3 , the same being shown in Fig. 3 as attached to the collar g^2 , and the inner end portion of said screw fitting loosely in the annular groove g' ,—whereby the arm G is mounted on the screw spindle F in a way to be restrained from sliding along the plain part g of the screw, and at the same time is free to turn upon the screw spindle. The carrying arm G is positioned intermediate the gripper heads D E of the stretching mechanism, and this carrying member supports several parts of the binder locking means so that said latter means may in one position operate for the purpose of bending the free end portions of the binder x , whereas said binder locking means is adapted by the turning movement of the arm G upon screw spindle F to be shifted into the out-of-service position when it is desired to stretch the binder around the shipping package.

The carrier arm G is provided at its free end with a transverse aperture h in which is fitted a stem H held in a fixed position in the carrier arm by a binding screw h' , see Fig. 3. The lower part of this stem is enlarged to form a clamping member I, shown more particularly in Figs. 3 and 4, the same being adapted for contact with a binder seal so as to retain said binder seal in a stationary position during the operation of bending the end portions of a binder into locking engagement with said seal. The retaining member I is provided with an active or working face consisting of a rib i and a plurality of grooves i' , shown more particularly in Fig. 3. The upper part of the stem H passes above the free end of the arm G, and on the protruding end of the stem is fitted the collar i^2 of a pressure head I', the latter being fixedly secured to the stem by a binding screw i^3 , see Fig. 3. The operator applies pressure to the head I', and the stem H, so as to force the retaining member I into contact with the seal x' , and while the seal is thus held fixedly in position by the pressure of the retaining member the end portions of the binder x are twisted or bent into locking engagement with the seal x' by the action of certain bending members or jaws J J' which are carried by a rotatable head J², said head and the two jaws constituting one element shown in detail in Fig. 7. The rotatable head J² is fitted loosely on the lower part of the stem H so as to occupy the space be-

tween the retaining member I and the free end of the carrying arm G, as shown clearly in Fig. 4, said rotatable head J² being thus mounted on the stem in a manner for the 5 stem to serve as the axis of rotation of the head. The head J² is confined or held against sliding movement by and between the retaining member I and the free end of carrying arm G, but as heretofore mentioned 10 the head is free to turn around the stem H in order that the jaws J J' may have rotative movement with respect to retaining member I. The jaws J J' depend from the 15 under face of the rotatable head, and in one position of the head said jaws J J' are in alinement with the retaining member I and on opposite sides thereof, see Figs. 4 and 5. The jaws are provided with means for engagement with the end portions of the 20 binder a, said means being preferably in the form of ribs j which depend from the under faces of the jaws. The ribs j of the bending jaws are similar to the rib i' of the retaining member, and in the first position 25 of the jaws with respect to the retaining member said ribs j of the jaws are in alinement with the ribs i of the retaining member, as shown in Fig. 5, whereby the retaining member is adapted to have the desired 30 contact with the seal for holding the latter fixedly in position, whereas the bending jaws are adapted through their ribs j for contact with the end portions of the binder. The jaws partake of the rotative 35 movement of the head J² in order to twist or bend the end portions of the binder into locking engagement with the seal, as shown in Fig. 8, said jaws being movable in arcuate paths and these paths are parallel to the 40 plane of the retaining member. Suitable means are provided for imparting rotative movement to the head J² and the jaws thereon, and in one embodiment of means shown particularly in Figs. 1, 2, 3, 4 and 5 said 45 means consists of a lever arm K provided with a hand-grip k and attached to a short upstanding post k', which post is secured to the head J² by a transverse pin k². The lever arm is attached to the rotatable head 50 so as to be entirely out of the way of the gripper heads D E of the binder stretching mechanism, and while the retaining member I is being pressed into contact with the seal this lever arm is operated to turn the head 55 J² around stem H, the effect of which is to twist or bend the end portions of the binder x around the seal x' and into locking engagement therewith.

The binder locking or sealing mechanism 60 heretofore described is used in conjunction with a wire binder x and a seal x', the latter being shown more particularly in Fig. 9. This seal forms the subject matter of a separate application filed on even date herewith, but as herein disclosed the seal is com-

posed of a single piece of metal which is doubled to produce tubular members and an intervening groove x², see Fig. 9. The operation of the device as thus far described is as follows:—

The screw spindle F is lifted out of the notch or recess e of the supporting member A, and thus the heads D E and the binder-locking device may be turned on the rod C so as to be out of the way. The head and the mechanism carried thereby is raised or lowered according to the height of the shipping case, after which the head is fastened in position by tightening the binding screw b' into contact with the post a. A shipping package, as X, is placed upon the table below the operating mechanism, after which the wire binder x is passed around the case so that the end portions of the binder overlap. The stretching device is now turned into position for operation, as shown in Figs. 1 and 2, the smooth part f' of the screw spindle being received into notch or recess e of head A. The gripper heads D E are positioned into contact substantially with the top of the case X so that the end portions of the binder x will be received in the spaces between jaws d' d³ of the grippers, after which the levers d⁴ are turned downwardly so as to move the jaws d³ toward the jaws d', as a result of which one end portion of the wire is gripped in the head D, whereas the other end portion of the wire is gripped in head E. With the seal locking device turned backwardly, the operator fits or adjusts the seal x' so that the overlapping ends of the binder will be received in the tubular members of the seal, the latter resting upon the packing case. Before or after adjusting the seal, the screw spindle F is rotated in a direction to draw the heads D, E toward each other, and thus the binder is stretched in two directions around the packing case, the end portions of the binder sliding through the tubular members of the seal during the stretching operation so as to assume the dotted line position of Fig. 8. The binder locking means is now turned by swinging the arm G around the smooth portion g of the screw spindle, the effect of which is to lower the entire seal locking device into operative position between the gripper heads of the stretching device. The seal-retaining member I engages with the seal so that the rib i of the member I fits in a groove x² of the seal, whereas the tubular members of said seal are received in the grooves i' in the under face of the retaining member I, the effect of which is to interlock the member I with the seal x', as shown in Fig. 3. Pressure is now applied by the hand of the operator to the head I' in order to forcibly hold the member I in contact with the seal so as to prevent the latter from turning,

and the operator now applies power to the lever arm K for the purpose of rotating the head J² around the spindle H, as a result of which the ribs j of the jaws J J' will bend 5 the straight end portions of the binder x into parallel relation to the tubular members of the seal x', thereby locking the end portions of the binder to the seal. The arm G is now swung out of position so as to withdraw 10 the bending members and the retaining member from contact with the seal and the binder, after which the cam levers d⁴ of the grippers are operated so as to release the heads D E from the binder, and the 15 entire device including the stretching means and the bending means are now lifted out of operative position by swinging the screw spindle F upwardly and rearwardly, thus removing the stretching and bending implement 20 from the shipping package and its binder, so that the shipping package can be either removed from the table or reversed in position so that other binders can be applied thereto in the manner described.

In Figs. 10 to 16 there are illustrated, 25 first, another form of the binder and the seal to be used in connection therewith, and, second, another embodiment of the binder fastening or locking mechanism whereby the seal is compressed and the binder is upset 30 in order to effect the locking or sealing of the binder, said binder locking mechanism operating in substantially the manner hereinbefore described and being used in connection with a stretching mechanism for placing tension upon the binder x. The binder shown is a flat metal band Z of a 35 form commonly known as a box strap, the meeting end portions of said binder being interlocked with a seal Z', said seal being shown in Figs. 15 and 16, and the upset portions of the band being shown in Figs. 11 and 12. The stretching device embodies the supporting head A, guide rod C, gripping heads D E, power screw F and the parts related thereto, all as hereinbefore described 40 in connection with the stretching mechanism for placing tension upon the band for the major part of its length by leaving the end portions of said band free or unconfined 45 in order to permit ready application thereto of the seal Z'. The binder fastening and sealing means embodies the swinging arm G mounted for rotative movement upon the plain and grooved portion g' of the screw spindle, but in order to upset the lapping portions of the flat metal band or strap and to interlock the same with the seal I find it desirable to employ the form of binder-locking mechanism illustrated more particularly in Figs. 10, 11, 12, 13 and 14. Loosely connected with the free end of the carrying member G is a frame member L, the same being provided with an anvil plate M and with an upstanding shank l, to which shank

is pivoted a link N, the latter serving as an operative connection between the frame member and the swinging arm G, whereby the frame member is adapted for movement relative to the arm G in order to position 70 the anvil plate M below the strap Z. This anvil plate is provided on its upper face with ledges m which are separated by an intervening space. Cooperating with the anvil plate is a complementary anvil O, the same being positioned above the plate M and pivotally connected therewith by a transverse pin o, the under face of said anvil O being provided with a rib o' positioned intermediate certain recesses o². The 75 pivoted anvil O is spaced relative to the anvil plate M so that the overlapping end portions z of the strap Z may be received between the anvil plate M and the anvil O. The frame member L is slotted to receive 80 the head p of a cam lever P, the latter being fulcrumed by a pin p' in the slotted part of the frame member, the head of said cam lever being positioned for contact with the pivoted anvil plate O. A pressure screw 85 may be substituted for cam lever P.

In operation the binder-locking mechanism is swung rearwardly by turning the arm G on the screw F, and the stretching mechanism is shifted into an out-of-service position by shifting the screw F out of the notch or recess in the head A. The box is placed upon the table below the stretching mechanism, and the strap Z is fitted around the box while the stretching mechanism is in said out-of-service position. The stretcher device is swung forwardly and downwardly in order that the grippers of the heads D E may engage with the band or strap adjacent the overlapping end portions z thereof, and thereafter the seal Z' is slipped upon the lapping end portions of the band so that the seal occupies a position intermediate the gripper heads D E. With the binder locking mechanism adjusted to the out-of-service position, the operator rotates the screw F for drawing the heads D E toward each other so as to place tension upon the band for the major part of its length, the end portions of said band sliding freely through the seal Z'. The stretching operation having been completed so as to place the desired tension upon the band, the binder-locking means are now swung forwardly so that the anvil plate M passes below the lapping portions of the band, said lapping portions and the seal being received between the operating faces of the complementary parts M O. The operator now applies power to the lever P, the cam head of which forcibly depresses the anvil O upon the seal and the lapping end portions of the binder. The ledges m of the anvil plate and the ledge o' of the anvil act upon the lapped portions of the binder and

upon the seal in a manner to upset the end portions of the binder and to compress the seal, the effect of which is to interlock the two parts of the binder with each other and 5 with the seal, as clearly shown in Figs. 11 and 12. The binder having been stretched, and its ends locked and sealed, the lever P is operated to release the parts M O, and the binder-locking means are shifted out of the 10 operative position. The cam levers of the gripper heads D E are now released and the stretching mechanism is withdrawn from the binder by lifting screw F out of the notch in the head A, thereby releasing 15 the binder-locking devices and the binder-stretching devices and allowing the binder in a locked condition to remain in contact with the shipping package. Said package may either be removed from the machine 20 or it may be reversed in position below the stretching and locking devices in order that the desired operations may be repeated in connection with another binder.

Having thus fully described the invention, what I claim as new and desire to secure by Letters Patent is:

1. In an implement for applying and fastening a package binder, the combination with binder-tensioning means, of binder-locking means shiftable at will into out-of-service relation to said binder-tensioning means, said binder-locking means including a rotatable member which, in the operative position of the binder-locking means, is operable for locking the end portions of a binder.

2. In an implement for applying and fastening a package binder, the combination with binder-tensioning means, binder-locking means pivoted for movement into an out-of-service relation to the binder-tensioning means, said binder locking means including a member rotatable on an axis extending at an angle to the axis of movement of said binder-locking means when shifted into and out of the service position.

3. In an implement for applying and fastening a package binder, the combination with binder-tensioning means, of binder-locking means shiftable at will into and out-of-service relation to said binder-tensioning means, said binder-locking means including a seal-part retaining member and a bending member rotatable with respect to said seal-part retaining member.

4. In an implement for applying and fastening a package binder, the combination with binder-tensioning means, of binder-locking means including a retaining member adapted for the reception of a seal-part and a bending member separate from said retaining member and rotatable relatively thereto.

5. In an implement for applying and fastening a package binder, a member operable

for positioning the implement relatively to an object, binder-tensioning means connected with said member and shiftable into an out-of-service relation to said member, and binder locking means operable in the service 70 position for deforming the end portions of a binder, said binder-locking means being carried by the binder tensioning member and shiftable therewith into and out of service positions.

6. In an implement for applying and fastening a package binder, a member, binder tensioning means shiftable relatively to said member, and binder locking means shiftable with said binder-tensioning means, said binder locking means in the service position thereof being rotatable for twisting the end portions of a binder.

7. In an implement for applying and fastening package binders, a supporting member, binder-stretching means mounted on said supporting member, said binder-stretching means being shiftable relatively to said supporting member to assume an out-of-service relation to a package to be bound, 80 and binder-locking means movable with said binder-stretching means into said out-of-service position.

8. In an implement for applying and fastening a package binder, the combination with a supporting member, of binder-stretching means including a rod fixedly attached to said supporting member, said binder-stretching means being shiftable by a rotative movement into an out-of-service position, and binder-locking means mounted in position for deforming the end portions of a binder subsequent to the action of the binder-stretching means in placing tension upon said binder.

9. In an implement for applying and fastening a package binder, the combination with binder-tensioning means for applying tension at separated points to the binder to be stretched, of binder-fastening means including a retaining member for a seal-part and a head positioned for operation upon the binder at a point intermediate the separated tension points, said binder-fastening head being rotatable with respect to said retaining member and operable for twisting the end portions of a binder into engagement with a seal-part.

10. In an implement for applying and fastening a package binder, the combination with binder-tensioning means for applying tension at separated points to a binder the ends of which are in crossing relation, of a binder-fastening means positioned for operation upon the crossing portions of the binder and intermediate the points of tension application by said binder-tensioning means, said binder-fastening means including a retaining member for a seal-part and a rotatable head operable for twisting said 120

end portions of the binder into locking engagement with a seal-part.

11. In an implement for applying and fastening a package binder, the combination of binder-tensioning means operable for applying tension at separated points to a binder the ends of which are in crossing relation, of a retaining member for holding a seal part in a fixed position relatively to end portions of a binder, and a binder-twisting head positioned for operation upon said end portions of the binder and intermediate the points of applying tension thereto by said binder-tensioning means, said binder-twisting head being rotatable with respect to said retaining member and operable for locking the crossing portions of the binder.

12. In an implement for applying and fastening a package binder, the combination of binder-tensioning means for applying tension at separated points to a binder, and binder-fastening means including a retaining member for holding parallel lengths of a wire and a rotatable twisting element position for action upon said parallel lengths of the binder at a point intermediate the separated points of applying strain thereto, said rotatable twisting element being operable independently of the action of the binder tensioning means.

13. In an implement of the class described, binder-sealing means embodying a seal-retaining member having means for applying pressure to a seal for fixedly retaining the same in position and a plurality of bending members mounted for rotative movement with respect to said seal-retaining member.

14. In an implement of the class described, binder-sealing means embodying a seal-retaining member operable for applying pressure to a seal for fixedly retaining the latter in position, a plurality of bending members positioned at opposite sides of said retaining member, and means for imparting rotative movement to said bending members while the retaining member is at rest.

15. In an implement of the class described, binder-sealing means embodying a movable carrier, a seal-retaining member supported by the carrier, said retaining member being fashioned for locking engagement with a seal to be fastened, means whereby pressure may be applied to the retaining member for clamping a seal in a fixed position, a plurality of bending members positioned at opposite sides of said retaining member, and means for imparting rotative movement to said bending members with respect to the retaining member.

16. In an implement of the class described, binder-sealing means embodying a seal retaining member, means for pressing said member into contact with a seal, a plurality of bending members, and means for impart-

ing rotative movement simultaneously to said bending members.

17. In a device of the class described, a seal-retaining member, binder-stretching means operable for placing tension upon a binder and for straining said binder so as to overlap the end portions thereof at the point to be occupied by the seal adapted to be held by said retaining member, and bending means rotatable relatively to the seal-retaining member for twisting said end portions of the binder under tension into locking engagement with said seal.

18. In a device of the class described, binder-sealing means embodying a carrier member movable on a transverse axis, a seal-clamping member supported by said carrier member, a rotatable head mounted to turn around an axis afforded by said seal-clamping member, said rotatable head being provided with bending jaws positioned substantially in the plane of the operating end of the seal-clamping member, and means for imparting rotative movement to said head.

19. In a device of the class described, binder-stretching means including a plurality of relatively movable gripper heads and operating means therefor, combined with binder-sealing means including a retaining member positioned for contact with a binder seal at a point intermediate said gripper heads, said binder-sealing means including also a plurality of bending members rotatable with respect to said retaining member and operable for bending the end portions of a binder into locking engagement with a seal.

20. In a device of the class described, binder-sealing means embodying a seal-retaining member for holding a seal fixedly in position upon a binder, a head rotatable on an axis afforded by said retaining member, bending jaws positioned in the plane of the retaining member, said jaws being movable with said rotatable head, and means whereby the head and said jaws are turned relatively to the retaining member.

21. In a device of the class described, binder-sealing means embodying a retaining member the working face of which is provided with means for holding a seal in position during the operation of bending a binder, a bending jaw the working face of which is provided with means for engagement with an end portion of a binder, and means for imparting rotative movement to the bending jaw relatively to the retaining member, said bending jaw being movable in a path lying substantially parallel to the plane of the retaining member.

22. In a device of the class described, binder-sealing means embodying a seal-retaining member, means for applying pressure to said seal-retaining member a plurality of bending jaws positioned in the

- plane of said retaining member, and means for imparting rotative movement to said bending jaws, the latter being movable in arcuate paths parallel to the plane of the retaining member. 23. In a device of the class described, binder-stretching means including a plurality of gripper heads and an operating screw therefor, combined with binder-sealing means including a carrier member mounted for rotative movement on said screw at a point intermediate said gripper heads, a seal-retaining member supported by the carrier member, and a plurality of bending jaws also supported by the carrier member and rotatable relatively to the seal-retaining member, said binder-sealing means being shiftable at will with respect to the gripper heads to assume an out-of-service relation with reference to the binder-stretching means. 24. In a device of the class described, a supporting head, and binder-stretching means including a guide rod and an operating screw together with a plurality of gripper heads, said guide rod being fixed to the supporting head and the operating screw being movable with said gripper heads relatively to the supporting head for assuming an out-of-service position, combined with binder-sealing means supported by the operating screw and movable with said binder-stretching means into said out-of-service position. 25. In a device of the class described, a supporting member provided with a recess, a guide rod fixed to said member, a plurality of gripper heads slidable on said guide rod, and an operating screw having threaded connection with said gripper heads, said operating screw being positioned to occupy said recess of the supporting member and said screw and gripper heads being shiftable on the guide rod into an out-of-service position. 26. In an implement for applying and fastening package binders, the combination of binder-tensioning means for applying tension to said binder, a retaining member for holding end portions of said binder in parallel relation, and binder-locking means including a rotatable twisting member positioned for operation upon said binder intermediate the separated points of applying strain thereto. 27. In an implement for applying and fastening a package binder, the combination of binder-tensioning means, and binder-locking means in shiftable relation thereto, said binder locking means including a retaining member for holding end portions of a binder in side by side relation, and a twisting member co-operable with said retaining member and rotatable with respect thereto. 28. In an implement for applying and fastening a package binder, a binder-retaining member for holding the end portions of a binder in side by side relation, binder-tensioning means operable for placing tension on said binder, and a twisting member rotatable with respect to the binder retaining member. In testimony whereof I have hereunto subscribed my name this 3 day of December, 1919.

SPENCER C. CARY.
